Patented Oct. 14, 1975

237,197

PICK-UP CARTRIDGE

Leopold Frans Albert Agnes Maria Raport, Kessel-Lo,
Belgium, assignor to U.S. Philips Corporation, New
York, N.Y.

Filed Sept. 26, 1973, Ser. No. 400,881

Claims priority, application Switzerland Mar. 28, 1973

Term of patent 14 years

Int. Cl. D14—01

U.S. Cl. D26—14 D

FIG. 1 is a perspective view of the pick-up cartridge showing my new design;

FIG. 2 is a left side elevational view thereof;

FIG. 3 is a right side elevational view thereof;

FIG. 4 is a bottom plan view thereof;

FIG. 5 is a top plan view thereof;

FIG. 6 is a front elevational view thereof; and

FIG. 7 is a rear elevational view thereof.

I claim:

The ornamental design for a pick-up cartridge, as shown and described.
